Fig. 4

FIGURE 1 is a side elevational view of an ion sensing electrode embodying the design.

FIGURE 2 is a perspective view of the electrode.

FIGURE 3 is an enlarged end view showing the tip of the electrode.

FIGURE 4 is an enlarged perspective view of the tip of the electrode.

The side of the electrode not shown in FIGURE 1 is a mirror image of the side shown.

The broken away showing of a cord at the far right in FIGURES 1 and 2 indicates indeterminate length.

I claim:

The ornamental design for an ion sensing electrode or the like, substantially as shown and described.
